(57) **CLAIM**

The ornamental design for a faucet, as shown and described.

DESCRIPTION

FIG. 1 is a perspective view of a first embodiment of a faucet of the new design;

FIG. 2 is a front elevational view of the faucet of FIG. 1; FIG. 3 is a rear elevational view of the faucet of FIG. 1; FIG. 4 is a left side elevational view of the faucet of FIG. 1; FIG. 5 is a right side elevational view of the faucet of FIG. 1;

FIG. 6 is a top plan view of the faucet of FIG. 1;

FIG. 7 is a bottom plan view of the faucet of FIG. 1;

FIG. 8 is a second perspective view of the first embodiment of the faucet, wherein the broken line showing of a faucet handle is provided for illustrative purposes only and forms no part of the claimed design;

FIG. 9 is a perspective view of a second embodiment of a faucet of the new design;

FIG. 10 is a front elevational view of the faucet of FIG. 9; FIG. 11 is a rear elevational view of the faucet of FIG. 9; FIG. 12 is a left side elevational view of the faucet of FIG. 9;

FIG. 13 is a right side elevational view of the faucet of FIG. 9;

FIG. 14 is a top plan view of the faucet of FIG. 9; and,

FIG. 15 is a bottom plan view of the faucet of FIG. 9.

The portions of the figures shown in broken lines are not part of the claimed design and are for illustration only.
